UNITED STATES PATENT OFFICE.

MILTON B. REACH, OF SPRINGFIELD, MASSACHUSETTS, ASSIGNOR TO A. G. SPALDING & BROS. MANF'G CO., A CORPORATION OF MASSACHUSETTS.

HORIZONTAL-BAR STRUCTURE FOR GYMNASIUMS.

1,003,797.

Specification of Letters Patent. Patented Sept. 19, 1911.

Application filed May 29, 1911. Serial No. 629,997.

To all whom it may concern:

Be it known that I, MILTON B. REACH, citizen of the United States, residing at Springfield, Massachusetts, have invented 5 certain new and useful Improvements in Horizontal-Bar Structures for Gymnasiums, of which the following is a specification.

My invention relates to a horizontal bar structure particularly adapted for use in 10 gymnasiums where galleries are provided, and it consists in the features and combination and arrangement of parts hereinafter described and pointed out in the claims.

In the accompanying drawings Figure 1 15 is an end view of the horizontal bar structure in place in connection with the gallery of the gymnasium; Fig. 2 is a front view of the part shown in Fig. 1; Fig. 3 is a plan view of the arrangement of the hoisting 20 ropes.

In these drawings, 1 indicates the gallery with which the gymnasium is provided having a railing 2 and a supporting beam 3. The horizontal bar 4 is arranged at a 25 suitable distance from this gallery, and parallel therewith, the ends of the horizontal bar being connected with the gallery by braces consisting of rods 4', preferably of one inch pipe. These brace rods are pivoted 30 to the supporting beam 3 of the gallery at the points 5. From the ends of the horizontal bar supporting cables 6 extend upwardly, as shown in Fig. 1, and at an inclination rearwardly toward the side wall 35 of the gymnasium, the upper ends of these supporting cables being connected with a supporting rod or pipe 7 which is suitably mounted on the frame work of the building. Suitable turn buckles are provided at 8 for 40 securing proper tension of these supporting cables or straining connections. From the ends of the horizontal bar other straining connections or cables 9 extend downwardly and these are connected with the floor 45 through any suitable form of turn buckle or straining means such as the lever device shown at 10; for instance this may be of the form shown in Letters Patent of the United States granted to me August 24, 1909, No. 932,413. The cables or lower connections 9 I prefer to extend vertically, while, as above stated, the upper 50 connections 6 extend backwardly at an inclination. When these cables or straining 55 connections are placed under tension, the

horizontal bar will be held rigidly in position, it being observed from Fig. 1 that the strain exerted by these connections being in different planes at angles to each other, and these planes being at an inclination to the plane of inclined pivoted supporting pipes or tubes 4', tendency of the horizontal bar to move in any direction will be resisted, it being further observed that the supporting rods or tubes 4' extend upwardly at an 60 inclination and also outwardly at an inclination, as shown in Fig. 2.

One feature of my present invention consists in the arrangement of the horizontal bar structure in connection with the gallery, so that it may be conveniently supported thereon and may be raised from its position of use to occupy a position adjacent the gallery, where it would be out of the way and leave the floor space entirely 70 clear. For this purpose the supporting tubes, as above stated, are pivotally mounted at the points 5, and a suitable hoisting rope 11 extends over a pulley 12 and having branches 13 and 14 passing around pulleys 15 and 16 to connect with the horizontal bar at or near the ends thereof. As shown in Fig. 2, the horizontal bar may be of double length, in which event there would be three sets of straining connections 80 and three of the pivoted tubes or bars 4'. In Fig. 1 I indicate in dotted lines the horizontal bar as having been hoisted to its position of non-use, this being accomplished by releasing the connections at 10 and drawing 85 upon the hoisting rope 11.

I claim as my invention:—

1. A horizontal bar structure for gymnasiums comprising the bar proper, bracing rods connected with the bar acting as a 95 carrier therefor, extending laterally therefrom, and pivotally mounted on a suitable supporting member, flexible straining connections extending upwardly from the horizontal bar and attached at a point overhead, flexible straining connections extending downwardly from the horizontal bar and attached to the floor, with suitable means for placing these connections under strain, and means for swinging the bracing rods on their pivots substantially as described.

2. A horizontal bar structure for gymnasiums comprising the bar proper, bracing rods connected with the bar, and pivotally 100 105 110

- mounted on a suitable supporting member, flexible straining connections extending upwardly from the horizontal bar and attached at a point overhead, and flexible straining connections extending downwardly from the horizontal bar and attached to the floor, with suitable means for placing these connections under strain, the upper straining connections inclining rearwardly in respect to the bar and the lower connections extending vertically, substantially as described.
3. In combination in horizontal bar structures for gymnasiums, a bar proper, rods connected thereto extending laterally therefrom and inclining in respect thereto, said rods being pivotally mounted to a supporting frame, and upwardly and downwardly extending flexible straining connections with means for adjusting the same, and means for swinging said laterally extend-

ing rods upwardly to raise the horizontal bar with its straining connections substantially as described.

4. In combination with the gallery of a 25 gymnasium, a horizontal bar extending parallel with the front of said gallery, rods pivotally mounted on the gallery extending laterally in respect thereto and connected with the horizontal bar, and upper and lower straining connections between the horizontal bar and the frame work of the building, and means for hoisting the horizontal bar into position adjacent the gallery to thus clear the floor, substantially as 30 35 described.

In testimony whereof, I affix my signature in presence of two witnesses.

MILTON B. REACH.
